UNITED STATES PATENT OFFICE.

CHARLES B. LONGSTRETH, OF DENVER, COLORADO.

REFRIGERATOR.

Application filed February 24, 1927. Serial No. 170,520.

This invention relates to improvements in the construction of refrigerators of the type employed in meat markets and stores.

It is evident that ice boxes and refrigerating cases containing articles of food, such as meat must be kept very clean in order to prevent the food becoming tainted. With the construction of ice boxes now commonly employed, the bottom of the compartment containing the ice can only be cleaned by first removing the ice and then removing the slat bottom on which the ice pieces are supported. It is evident, therefore, that it requires a large amount of labor to properly clean an ice box of this type constructed in the usual manner and therefore this cleaning operation is oftentimes neglected with the result that the bottom of the ice compartment becomes covered with a slime which gives it an unsanitary appearance.

It is the object of this invention to produce an ice box of such a construction that the bottom of the ice compartment and of the drainage trough can readily be cleaned without making it necessary to remove the ice.

The construction briefly described consists in forming the bottom of the ice compartment of several removable sections, which can be removed and replaced from below. This makes it possible for a person to enter the refrigerating chamber, detach one of the sections, take it outside and clean it, and then replace it, without disturbing the contents of the ice compartment. The drainage trough is also made removable so that it may readily be detached and cleaned.

In order to more clearly describe the invention and the preferred embodiment thereof, I shall now have reference to the accompanying drawings, in which an ice box constructed in accordance with this invention has been illustrated, and in which:

Fig. 1 is a vertical longitudinal section through one of the improved ice boxes;

Fig. 2 is a transverse section taken on line 2—2, Fig. 1;

Fig. 3 is a section taken on line 3—3, Fig. 2;

Fig. 4 is a section taken on line 4—4, Fig. 2;

Fig. 5 is a section taken on line 5—5, Fig. 3;

Fig. 6 is a section taken on line 6—6, Fig. 2; and

Fig. 7 is a section taken on line 7—7, Fig. 1.

In the drawings the invention has been shown as embodied in the construction of an ice box of usual form, which has a top 1, rear wall 2, floor 3, sides 4 and 5, and whose

front side is provided with doors 6 and 7, the door 6 opening into the refrigerating chamber and door 7 closing the entrance to the ice compartment. The ice in the upper compartment is supported on a series of parallel slats 8 which are connected by means of transverse pieces 9 so as to form several slat sections that can be readily removed and applied in place. These slat sections are supported on transverse joists 10, 11, 12 and 13, which extend from the front of the case to the rear thereof. The upper edges of these joists are protected by means of sheet metal strips 14 and 15. The strips 14 are of Z shape cross-section and have one side or flange secured to the inner surface of the refrigerator and are provided with downwardly extending flanges 16, which are parallel with and spaced from the surfaces of the joists 10 and 13, in the manner shown most clearly in Figure 3. Secured to the upper edges of joists 11 and 12 are sheet metal protectors having a U-shaped cross-section. The sides 17 of these protectors extend down parallel to the sides of the joists, but are spaced a short distance from the latter. For the purpose of holding the ice in position on the slats 8, vertical sides 18 and 19 have been provided along each side of the refrigerator in the manner shown in Figures 1 and 2.

Between each pair of joists, like 10 and 11, 11 and 12, and 12 and 13, removable bottom sections 20 have been provided. These sections are preferably duplicates, and are formed with board bottoms 21 whose ends are secured to strips 22. The space between the strips 22 is filled with a cork insulating material 23. A sheet metal plate 24 is provided on top of the cork insulator 23 and is nailed or otherwise secured to the strips 22. The edges of the sheet metal plate are bent at right angles to the body portion thereof in the manner indicated by reference numeral 25. These edges extend up into the space between the joists and the flanges 16 and 17. With this construction any water that flows downwardly over the metal protectors 14 and 15 will be deposited on the metal plate 24. By referring to Figure 2, it will be seen that the removable bottom plates 20 are so connected to the joists that they are inclined in a transverse direction. The right hand end of the sections (Fig. 2) is higher than the left hand end, so that the water will flow towards the left. A removable drainage trough 26 is supported beneath the lower ends of these re-

movable sections, and the metal plate 24 has its edge 27 bent downwardly in the manner shown in Fig. 2 so as to direct the water into the trough 26. The removable sections are supported in the following manner. Short bars 28 are secured to the underside of the joists and extend into the space between them. These bars form supports for the lower ends of the removable bottom sections 20. Secured 10 to the lower surface of the upper end of the removable sections, near each corner, are bars 29, which project beyond the ends of the sections and are adapted to be engaged by the horizontal portions 30 of the L-shaped supports whose vertical sides 39 are pivoted at 40. These L-shaped members may be swung into position underneath the bars 29, in the manner shown in Figs. 2 and 3, and will serve to removably support the bottom sections. 20 When the sections are to be removed for cleaning the L-shaped supporting members are swung out of supporting position, after which the sections may be withdrawn from their position on the bars 28, after which 25 they may be taken out, cleaned and replaced. The supporting means which I have described is very well adapted for this purpose, but it may be replaced by any other suitable means. The upper end of the bottom sections are provided with a transverse member 41, which fits against the lower edges of the vertical wall members 42 and 43, so as to form a passage 44 through which the warm air may pass upwardly. After the air from the refrigerator 30 chamber arrives at the top of the walls 42 and 43, it flows over the ice in the ice compartment and after it has been cooled, it enters the refrigerator chamber through the passage 45. The water from the melting ice flows 40 from the bottom sections into the trough 26, which is lined with sheet metal, and after flowing through the trap 46 flows out through a suitable drain. One end of this trough is supported on an angle iron bracket 47 and the other is supported on a hinged bar 48, one end of which is pivoted at 49 to the horizontal portion of an L-shaped bracket 50, while the free end swings into and out of contact with the horizontal portion of the 45 other support (Fig. 7). When the trough is to be removed and cleaned, it is only necessary to swing the bar 48 from its support- 50

ing position, whereby the trough is released and can be quickly removed.

The ends of the protecting members 14 and 15 are formed with rolls 51 that prevent the water from passing off onto the joists. 55

From the above it will be apparent that I have produced an ice box construction which can be easily cleaned and which can therefore be maintained in a sanitary condition with the least possible trouble. The gist of the invention resides in the sectional construction of the bottom of the ice chamber which permits ready removal and replacement of these 60 sections from below. 65

Having described the invention what is claimed as new is:

1. An ice box having an ice chamber near its top, and a refrigerating chamber beneath the ice chamber, a plurality of transversely extending parallel joists between said chambers, a bottom section located between each pair of joists, means for detachably securing said sections in place, said bottom sections filling the space between the joists and having their upper surfaces covered by a metal sheet whose opposite edges are bent upwardly so as to form upwardly extending flanges and protectors secured to the joists and provided with flanges that extend downwardly beyond the upper edges of and overlap the flanges on the bottom sections. 70 75

2. In an ice box having an upper ice chamber and a lower refrigeration chamber separated by a partition on which the ice is supported, a pair of spaced parallel joists extending transversely of the box, a sheet metal protector secured to the upper edge of the joists, said protectors having flanges 80 that are spaced from and parallel to the sides of the joists, a removable bottom section located between each pair of joists, each bottom section filling the space between the joists and having its upper surface covered 85 with sheet metal, the opposite sides of the sheet metal being bent at right angles to the body portion thereof so as to form flanges that extend into the space between the joists and the flanges of the protectors and means 90 for removably securing the bottom sections in place between the joists. 95 100

In testimony whereof I affix my signature.

CHARLES B LONGSTRETH.
